CLAIM

The ornamental design for a hand-held massager, as shown and described.

DESCRIPTION

FIG. 1 is a top plan view of a hand-held massager showing our new design;

FIG. 2 is a front elevational view thereof, the rear view being identical;

FIG. 3 is a side elevational view thereof, the opposite side being identical;

FIG. 4 is a bottom plan view thereof; and

FIG. 5 is a cross-sectional view taken along line 5—5 of FIG. 2.

FIG. 1

FIG. 2

FIG. 3

FIG. 5

FIG. 4
